METERING FUEL PUMP

William E. Leibing, Los Angeles, Calif.

Application December 13, 1948, Serial No. 65,031

5 Claims. (Cl. 103—161)

1

This invention relates to improvements in metering fuel pumps for internal combustion engines and is particularly directed toward the provision of altitude compensating mechanism for regulating the rate of fuel delivery from the pump to promote most efficient operation of the engine at various altitudes. This invention is useful in connection with internal combustion engines as employed in automobiles, trucks and buses, as well as in aircraft.

Internal combustion engines are commonly provided with means in the fuel system for regulating the richness of the mixture so that the proper proportions of fuel and air can be admitted to the engine. Such adjustments are ordinarily made to meet sea level conditions; that is, the fuel delivery at full load and the fuel delivery at idling are adjusted so that the engine operates at a maximum efficiency under the barometric pressure existing at sea level. If the engine as adjusted is later operated at high elevation the lower barometric pressure has the effect of reducing the proportion of air admitted for combustion, with the result that the fuel air mixture becomes too rich. The problem of making proper correction for altitude is complicated by the fact that it has been found that substantially no correction is required for idling. It is known that the flow of air through a restriction increases in proportion to the pressure difference across the restriction up to a certain point. Thus air flow through a throttle valve of an engine under the action of manifold vacuum pressure increases in proportion to the vacuum up to about fourteen inches of mercury, but higher vacuum pressures do not appreciably increase the flow at all. Hence, the throttle valve on the internal combustion engine which normally idles at sea level with about twenty inches of mercury vacuum in the intake manifold will pass the same amount of air at six thousand feet altitude as it will at sea level, and therefore the same amount of fuel should be delivered to the engine when idling at six thousand feet as when idling at sea level.

Accordingly, it is the principal object of this invention to provide a metering fuel pump for an internal combustion engine which includes altitude correction means for reducing the richness of the mixture when the engine is operating under load but which does not reduce the rate of fuel delivery for idling regardless of altitude.

Another object is to provide a metering fuel pump having altitude correction means which embodies certain improvements over my copend-

2

ing applications, Serial No. 739,106, filed December 1, 1947, and Serial No. 7,250, filed February 9, 1948, which matured into Patent No. 2,557,508 on June 19, 1951.

Another object is to provide a sealed metallic bellows or the like operable through a yoke to reduce the output of the fuel pump when atmospheric pressure is reduced.

Other objects and advantages will appear hereinafter.

In the drawings:

Figure 1 is a sectional plan view showing a preferred embodiment of my invention.

Figure 2 is a transverse sectional elevation taken substantially on the lines 2—2 as shown in Figure 1.

Figure 3 is a longitudinal section taken substantially on the lines 3—3 as shown in Figure 1.

Figure 4 is a perspective view showing a preferred construction of the yoke.

Referring to the drawings, a casing 10 is provided with spaced aligned bearings 11 and 12 for supporting a rotor shaft 13 adapted to be driven from its projecting end 14. The projecting end 14 is provided with a suitable keyway 15 so that the shaft may be driven in timed relation with the rotation of the crank shaft or cam shaft of an internal combustion engine. A rotor 16 is fixed on the shaft and turns within the casing 10.

The rotor is provided with a single or double series of positive displacement pump elements generally designated 17. Each of these pump elements includes a radially movable piston 18, a flexible sealing diaphragm 19, and a compression spring 20. A sleeve 21 encircles the rotor 16 and is adapted to rotate therewith. The sleeve 21 is carried on a bearing 22 within a ring 23 which is pivotally mounted on the housing at 24.

Clearance is provided within the housing so that the ring 23 can be shifted about its pivotal support 24. Such shifting movement of the ring 23 and sleeve 21 relative to the rotor 16 develops eccentricity of the sleeve 21 and hence the individual pump pistons 18 reciprocate radially as the rotor 16 is turned. This reciprocation is used

to pump fuel from an inlet 25 to spaced outlets 26 and 27. The passage of the fuel from the inlet 25 to the outlet 26 is by way of the passageway 28, chamber 29, inlet passage 30 and port 31 in

the sealing washer 32. The discharge from the series of pump units 17 on the left side of the rotor 16 as viewed in Figure 3 occurs through outlet port 33 in the washer 32, outlet passage 34 and chamber 35.

The member 36 which supports the sealing washer 32 may be resiliently supported on the

the springs 37. The right hand series of pump units 17 as shown in Figure 6 act to pump fuel from the inlet 25 to the outlet 27 by way of the sealing washer 38. The porting and series of passageways for the sealing washer 38 are similar to those described in connection with the sealing washer 32.

Means are provided for shifting the ring 23 in response to variations in vacuum pressure in the inlet manifold of the internal combustion engine. The vacuum pressure is communicated to the vacuum chamber 39 by way of the inlet 40. The flexible diaphragm 41 at one end of the chamber 39 is connected to a control element 42 which extends through the diaphragm 41 and forms a seal therewith. The control element 42 is provided with a central projection 43 which carries a transverse pin 44. A lever 45 which comprises a pair of duplicate elements 46 is pivoted at one end to the pin 44 and at the other end to the pin 47. The pin 47 is mounted in the member 48 which is pivotally supported in the housing 10 on the pivot pin 49. The spring 50 acts to maintain the member against the adjustable stop 51. A link 52 is pivotally connected to the lever at 53 and to the ring 23 at 54. Accordingly, movement of the control member 42 moves the lever 45 about the pivot pin 47 and hence shifts the ring 23 about its pivotal support 24. A spring 55 is mounted within the chamber 39. This spring engages the member 42 at one end and a stop collar 56 at the other end. An adjustable set screw 57 extends through the wall of the casing to contact the stop collar 56.

A yoke member generally designated 58 is formed of a pair of end sections 59 and 60, each having an oval shaped opening 61. The member 59 is provided with end walls 62 and 63 having tabs 64. The tabs 64 are adapted to extend through apertures 65 provided in the member 60, and the yoke assembly is completed by the insertion of suitable cotter pins 66 within the openings 67 to retain the members 59 and 60 in assembled relationship about the rotor 16. The oval shaped openings 61 are sufficiently large so that the yoke does not contact the rotor at any time. A pair of ears 68 are provided on the end wall 63, and these ears are pivotally mounted on the pin 44 so that the yoke 58 is pivotally connected to the control member 42.

A metallic seal bellows 70 is mounted within the housing 10 and is attached to the end wall 62 of the yoke 58 by means of a screw 71 or other suitable attachment means. The location of the bellows 70 is diametrically opposed to the location of the diaphragm 41. The outer end of the bellows 70 is carried on a threaded pin 72 which extends outwardly through the wall of the housing and is provided with a lock nut 73. The sealed bellows 70 may contain air if desired, but I prefer to use a gas with a low coefficient of expansion such as, for example, helium gas or hydrogen gas.

An arm 75 is fixed to the pivot shaft 49 at a location outside of the housing 10. This arm is adapted to be actuated by a suitable rod (not shown) in order to increase the rate of delivery of fuel under cold starting conditions. Counterclockwise movement of the lever 75 as shown in Figure 2 moves the fitting 48 to compress the spring 50 and to move the lower end of the lever 45 toward the left, thereby causing the links 52 to move the ring 23 to increase its eccentricity.

In operation the rotor shaft 13 is driven in timed relation with the engine and turns the

5 rotor 16 and sleeve 21 within the nonrotary ring 23. The position of the ring 23 determines the amount of eccentricity of the sleeve 21, and accordingly regulates the stroke of the individual pump units 17 as they rotate with the rotor 16. When the vacuum pressure in the engine manifold is high relatively little fuel is required. Thus, when the engine is idling the fuel requirements are at a minimum and the manifold vacuum pressure is high. This vacuum pressure is transmitted to the vacuum chamber 39. Atmospheric pressure within the casing acts on the exposed area of the diaphragm 41 and moves the control member 42 to the right as shown in Figure 2 against the action of the spring 55. Atmospheric air reaches the interior of the housing 10 by way of the screen plug assembly generally designated 74. When the engine is equipped with a super charger the screen plug assembly 74 is removed so that the interior of the housing 10 may be connected with the air induction system between the super charger and the throttle valve of the engine (not shown), so that the pressures within the housing are those pressures which are available to the engine.

20 The set screws 57 and 72 are adjusted so that the lower vacuum pressure, when the engine operates at full throttle and full load at sea level, is effective to provide the proper rate of fuel delivery.

25 When idling at sea level there is a balance between the spring 55 plus the effect of the bellows 70 on one hand and the resultant thrust on the diaphragm 41 under idling conditions on the other hand. The idling position of the control member 42 as thus determined does not change when the engine is operating at high altitude because the lower atmospheric pressure within the casing 10 is effective on both the exposed area of the diaphragm 41 and on the exposed area of the bellows 70. The lowering of the atmospheric pressure due to altitude, accordingly, has an effect on both the diaphragm and the bellows so that the net result is that the same amount of fuel is delivered to the engine when idling, regardless of elevation.

30 The diaphragm pump elements 17 which operate within the rotor are spring actuated toward their outer position, and as each of the springs 35 are of substantially equal tension it follows that the sleeve 21 always tends to center itself around the rotor, for when so centered all springs 20 within the rotor 16 are under equal compression. To shift the sleeve 21 to the position of maximum eccentricity as shown in Figure 2 requires a considerable effort of spring 55 and of bellows 70. The spring 55 and bellows 70 are correspondingly set at sea level to maintain the proper eccentricity of the sleeve 21 to deliver the correct amount of fuel to the engine for full power. Accordingly, when the engine operates under full load at a high altitude the bellows 70 becomes considerably weaker in that the internal pressure is greater than the external pressure. Accordingly, the yoke 58 will be shifted toward the right as viewed in Figure 2, reducing the eccentricity of the sleeve 21 and therefore reducing the amount of fuel pumped. Since the engine is operating at full load, the manifold vacuum pressure approaches zero, and hence the diaphragm 41 plays no part in positioning the yoke 58. It has been found from experience that intermediate positions between full throttle and idling position are well compensated for by the mechanism disclosed, and that once both limits or ex-

treme positions are chosen the intermediate positions operate satisfactorily.

A small amount of "grow" of the bellows 70 upon application of heat is a desirable feature for it acts as an automatic enrichment means for the engine upon cold starting conditions. By the proper selection of the size of the bellows any greater or lesser amount of correction for altitude can be obtained, and by using different gases within the bellows different degrees of automatic cold start effectiveness can be had.

Having fully described my invention, it is to be understood that I do not wish to be limited to the details herein set forth, but my invention is of the full scope of the appended claims.

I claim:

1. In a pump, the combination of a housing; a rotor mounted to turn in the housing; a plurality of positive displacement pump elements mounted for radial movement on the rotor; a rotatable sleeve encircling the rotor and cooperating with each of said pump elements; means including a movable member in the housing adapted to shift the sleeve to vary the stroke of the pump elements; vacuum operated means adapted to shift the position of said movable member and thereby vary the rate of delivery of fuel from said pump elements; altitude correction means including an expansible sealed member mounted within the housing on the opposite side of the rotor from said vacuum operated means; and means connecting the sealed member with said movable member whereby the sealed member may act in tension to oppose the action of the vacuum operated means under high vacuum conditions and to shift the movable member in a direction to reduce the stroke of the pump elements under low vacuum conditions.

2. In a pump, the combination of a housing; a rotor mounted to turn in the housing; a plurality of positive displacement pump elements mounted for radial movement on the rotor; a rotatable sleeve encircling the rotor and cooperating with each of said pumps; means including a movable member in the housing adapted to shift the sleeve to vary the stroke of the pump elements; vacuum operated means adapted to shift the position of said movable member and thereby vary the rate of delivery of fuel from said pump elements; altitude correction means including a sealed bellows mounted within the housing on the opposite side of the rotor from said vacuum operated means and coaxially therewith; and a yoke connecting the bellows member with said movable member whereby the bellows member may act in tension to oppose the action of the vacuum operated means under high vacuum conditions and to shift the movable member in a direction to reduce the stroke of the pump elements under low vacuum conditions.

3. In a fuel pump, the combination of a housing; a rotor mounted to turn in the housing; a plurality of positive displacement pump elements movably mounted on the rotor; a nonrotary ring in the housing having a rotatable sleeve thereon encircling the rotor and cooperating with each of said pumps, the ring and sleeve being shiftable to vary the stroke of the pump elements; a mov-

able member in the housing adapted to shift the ring; vacuum operated means adapted to shift the position of the member and thereby vary the rate of delivery of fuel from said pump elements; altitude correction means mounted within the housing on the opposite side of the rotor from said vacuum operated means for decreasing the fuel delivery rate from said pump elements, said means including a sealed bellows connected with 5 said movable member whereby movement of the control member under high vacuum conditions is resisted by lengthening of the bellows.

4. In a fuel pump, the combination of a housing; a rotor mounted to turn in the housing and driven by the engine; a plurality of positive displacement pump elements movably mounted on the rotor; a rotatable sleeve encircling the rotor and cooperating with each of said pumps; means including a movable member in the housing 10 adapted to shift the sleeve to vary the stroke of the pump elements; means actuated by vacuum pressure adapted to shift the position of said member and thereby vary the rate of delivery of fuel from said pump elements; and altitude correction means including a sealed bellows mounted 15 within the housing on the opposite side of the rotor from said vacuum operated means and connected with said movable member whereby movement of the control member under high vacuum conditions is resisted by lengthening of the bellows.

5. In a fuel pump, the combination of a housing; a rotor mounted to turn in the housing and driven by the engine; a plurality of positive displacement pump elements movably mounted on the rotor; a nonrotary ring in the housing having a rotatable sleeve thereon encircling the rotor and cooperating with each of said pumps, the ring and sleeve being shiftable to vary the stroke 20 of the pump elements; a movable member in the housing adapted to shift the ring; vacuum operated means adapted to shift the position of said member and thereby vary the rate of delivery of fuel from said pump elements; altitude correction means including a sealed bellows mounted within the housing on the opposite side of the rotor from said vacuum operated means and connected with said movable member whereby movement of the control member under high vacuum conditions is resisted by lengthening of the bellows.

30

6. In a fuel pump, the combination of a housing; a rotor mounted to turn in the housing and driven by the engine; a plurality of positive displacement pump elements movably mounted on the rotor; a nonrotary ring in the housing having a rotatable sleeve thereon encircling the rotor and cooperating with each of said pumps, the ring and sleeve being shiftable to vary the stroke 35 of the pump elements; a movable member in the housing adapted to shift the ring; vacuum operated means adapted to shift the position of said member and thereby vary the rate of delivery of fuel from said pump elements; altitude correction means including a sealed bellows mounted within the housing on the opposite side of the rotor from said vacuum operated means and connected with said movable member whereby movement of the control member under high vacuum conditions is resisted by lengthening of the bellows.

40

7. In a fuel pump, the combination of a housing; a rotor mounted to turn in the housing and driven by the engine; a plurality of positive displacement pump elements movably mounted on the rotor; a nonrotary ring in the housing having a rotatable sleeve thereon encircling the rotor and cooperating with each of said pumps, the ring and sleeve being shiftable to vary the stroke 45 of the pump elements; a movable member in the housing adapted to shift the ring; vacuum operated means adapted to shift the position of said member and thereby vary the rate of delivery of fuel from said pump elements; altitude correction means including a sealed bellows mounted within the housing on the opposite side of the rotor from said vacuum operated means and connected with said movable member whereby movement of the control member under high vacuum conditions is resisted by lengthening of the bellows.

45

8. In a fuel pump, the combination of a housing; a rotor mounted to turn in the housing and driven by the engine; a plurality of positive displacement pump elements movably mounted on the rotor; a nonrotary ring in the housing having a rotatable sleeve thereon encircling the rotor and cooperating with each of said pumps, the ring and sleeve being shiftable to vary the stroke 50 of the pump elements; a movable member in the housing adapted to shift the ring; vacuum operated means adapted to shift the position of said member and thereby vary the rate of delivery of fuel from said pump elements; altitude correction means including a sealed bellows mounted within the housing on the opposite side of the rotor from said vacuum operated means and connected with said movable member whereby movement of the control member under high vacuum conditions is resisted by lengthening of the bellows.

50

9. In a fuel pump, the combination of a housing; a rotor mounted to turn in the housing and driven by the engine; a plurality of positive displacement pump elements movably mounted on the rotor; a nonrotary ring in the housing having a rotatable sleeve thereon encircling the rotor and cooperating with each of said pumps, the ring and sleeve being shiftable to vary the stroke 55 of the pump elements; a movable member in the housing adapted to shift the ring; vacuum operated means adapted to shift the position of said member and thereby vary the rate of delivery of fuel from said pump elements; altitude correction means including a sealed bellows mounted within the housing on the opposite side of the rotor from said vacuum operated means and connected with said movable member whereby movement of the control member under high vacuum conditions is resisted by lengthening of the bellows.
